US00D627725S

(12) **United States Design Patent**
Gebert

(10) **Patent No.:** **US D627,725 S**
(45) **Date of Patent:** **** Nov. 23, 2010**

(54) **ROUND HOUSING FOR A DC SWITCH FOR AN INVERTER**

(75) Inventor: **Bernd Gebert**, Niestetal (DE)

(73) Assignee: **SMA Solar Technology AG**, Niestetal (DE)

(**) Term: **14 Years**

(21) Appl. No.: **29/343,790**

(22) Filed: **Sep. 18, 2009**

(51) **LOC (9) Cl.** **13-02**

(52) **U.S. Cl.** **D13/118; D13/110**

(58) **Field of Classification Search** **D13/110, D13/108, 118, 123, 162, 169, 174, 199; D8/307, D8/308, 310-314; D14/257, 432, 438; 16/404; 334/7, 10; 337/186; 361/600, 601, 730; 363/141, 142**

See application file for complete search history.

(57) **CLAIM**

The ornamental design for a round housing for a DC switch for an inverter, as shown and described.

DESCRIPTION

FIG. 1 is a front perspective view of a round housing for a DC switch for an inverter showing my new design;

FIG. 2 is a front view thereof;

FIG. 3 is a side view thereof;

FIG. 4 is a bottom plan view thereof; and,

FIG. 5 is a top plan view thereof.

The broken lines shown represent unclaimed subject matter and form no part of the claimed design.

1 Claim, 5 Drawing Sheets

FIG. 1

FIG. 2*FIG. 3*

FIG. 4

FIG. 5
